UNITED STATES PATENT OFFICE.

CHARLES J. WAGNER, OF ALMA, MISSOURI.

CARPET-STRETCHER.

SPECIFICATION forming part of Letters Patent No. 611,344, dated September 27, 1898.

Application filed July 3, 1897. Serial No. 643,438. (No model.)

To all whom it may concern:

Be it known that I, CHARLES J. WAGNER, a citizen of the United States, residing at Alma, in the county of Lafayette and State of Missouri, have invented a new and useful Carpet-Stretcher, of which the following is a specification.

The invention relates to improvements in carpet-stretchers.

10 The object of the present invention is to improve the construction of carpet-stretchers and to provide a simple and comparatively inexpensive one capable of easy manipulation and adapted to enable a carpet to be rapidly stretched without injuring the same.

15 The invention consists in the construction and novel combination of parts, as hereinafter fully described, illustrated in the accompanying drawings, and pointed out in the claims 20 hereto appended.

25 In the drawings, Figure 1 is a perspective view of a wire stretcher constructed in accordance with this invention. Fig. 2 is a longitudinal sectional view of the operating mechanism. Fig. 3 is a transverse sectional view. Fig. 4 is a detail perspective view of the carpet-engaging head. Fig. 5 is a similar view showing a modified form of head. Fig. 6 is a detail view illustrating the manner of 30 mounting the lever. Fig. 7 is a detail view of one of the bearing brackets or supports. Fig. 8 is a detail perspective view of the pivot of the lever.

35 Like numerals of reference designate corresponding parts in the several figures of the drawings.

1 designates a main bar, to which is slid- 40 ingly connected an extensible stretcher-bar 2, carrying a transverse carpet-engaging head 3. The sliding connection between the bars 1 and 2 is effected by means of a pair of op- 45 positely-disposed loops 4 and 5, each secured to one of said bars and receiving and forming a guide for the other.

45 The bar 1, which is stationary during the stretching operation, carries a longitudinal rack-bar 6, which is provided with teeth formed by depressions and having shoulders at one end and bevel-faces at the other. The 50 ratchet-bar 6 is engaged by an actuating-pawl 7, pivotally connected between its ends to an operating-lever 8, which is fulcrumed

on brackets or supports 9, secured to the side edges of the extensible bar 2. The brackets or supports 9, which are substantially inverted-V shaped, are provided at their apexes with bearing-recesses receiving a transverse pivot 10 of the operating-lever. The bearing-recesses are provided with narrow entrance portions, and the bearing portions at 55 the terminals of the pivot are recessed at one side to permit them to be readily introduced into the bearing-recesses when the lever is arranged in substantially a horizontal position. When the lever is in its operative position, the full diameter of the journal portions of the pivot is disposed transversely of the entrance slots or portions of the recesses, so that there is no liability of the lever becoming accidentally unshipped during the 60 stretching operation.

The lever, which is preferably provided at its engaging end with a sleeve or ferrule 8^a, has a bifurcation in which the actuating-pawl 7 is pivoted, and the said pawl is adapted to 75 engage the teeth or depressions of the ratchet-bar and obtains a firm hold on the latter to enable the extension-bar 2 to be forced outward by the operating-lever in stretching a carpet. The ferrule or sleeve 8^a is provided 75 at the inner side of the bifurcation with an extension 8^b, which projects beyond the lever and is adapted to engage the rear end of the actuating-pawl 7. The pawl 7 is pivoted between its ends in the bifurcation, and its 80 rear end, which is recessed, as shown, is adapted to be engaged by the said extension 8^b, whereby when the lever is swung backward 85 sufficiently to carry the extension 8^b into contact with the pawl the latter will be lifted out 90 of engagement with the teeth of the rack-bar. The loop 5 is provided with integral perforated ears, formed by cutting the top of the loop and bending the severed portions vertically, as clearly illustrated in Fig. 3 of the accompanying drawings. By oscillating the operating-lever the stretching-bar is gradually advanced until the carpet is stretched to the 95 desired extent.

The head 3, which engages the carpet, 100 consists of a transverse bar or piece provided with teeth or projections, and it may be constructed as illustrated in Fig. 4 of the accompanying drawings or as shown in Fig. 5, ac-

cording to the character of the carpet to be stretched. The inner edge of the head 3 is recessed to receive the end of the stretching-bar 2, and it is detachably secured to the same by means of a plate 12, which is perforated for the reception of screws or other suitable fastening devices. The fingers 13 of the head 3 are formed integral with a plate 14, while the fingers or projections of the head 3^a consist of separate pieces embedded in and projecting from the head and supported by a face-plate. The latter construction is stronger than the former and is adapted for operating on the heavier class of carpets.

15 A series of hinged bars 15, which are adapted to fold on each other, are connected with the inner end of the bar 1 by a hinge 16 and with each other by a hinge 17. Any number of the bars 15 may be employed, so that the 20 carpet-stretcher may obtain a bearing against the wall at one side of the room while stretching the carpet at the opposite side. The bars may be folded on each other when the device is not in use and also to shorten it to fit a 25 smaller room.

This invention has the following advantages: The carpet-stretcher is simple and comparatively inexpensive in construction, it is adjustable by means of the folding bars to fit 30 rooms of different sizes, and it is adapted to be readily extended to stretch a carpet to the desired extent.

What I claim is—

1. A carpet-stretcher comprising a main 35 bar, a rack-bar arranged on the upper face of the main bar and provided with depressions forming teeth, an extensible stretching-bar slidingly connected with the main bar, brackets mounted on the extensible bar, a lever fulcrumed on the bracket and having its lower end bifurcated and provided at the rear side 40 of the bifurcation with an extension, an actuating-pawl pivoted between its ends in the bifurcation of the lever, the rear end of the 45 pawl being arranged to be engaged by the said extension, whereby the lever is adapted to lift the pawl out of engagement with the rack-bar, and a check-pawl, substantially as described.

2. A carpet-stretcher comprising a main 50 bar provided with ratchet-teeth, a sliding stretching-bar provided with a carpet-engaging head, the oppositely-disposed loops 4 and 5 connecting the main bar and the stretching-bar, the loop 5 being provided with integral 55 ears formed by cutting the loop and bending the severed portions upward, a check-pawl pivoted between the perforated ears and engaging the ratchet-teeth, the brackets secured to the sliding bar at opposite sides thereof, and 60 an operating-lever fulcrumed on the brackets and provided with a pawl for engaging the ratchet-teeth, whereby the sliding bar is actuated, substantially as described.

3. A carpet-stretcher comprising a main 65 bar provided with ratchet-teeth, an extensible stretching-bar slidingly connected with the main bar, brackets rigidly mounted on the extensible bar and provided with bearing-openings having entrance-slots narrower than 70 the bearing-openings, an operating-lever provided with a transverse pivot 10, recessed at opposite sides to pass through the entrance-slots of the brackets, whereby the lever is detachably fulcrumed thereon, an actuating- 75 pawl carried by the lever, and a check-pawl, substantially as described.

4. A carpet-stretcher comprising a main rack-bar, an extensible stretching-bar slidingly connected with the main bar, a lever 80 fulcrumed on the extensible bar and provided at its lower end with a bifurcation and having an extension at the rear side of the bifurcation, an actuating-pawl pivoted between its ends in the bifurcation of the lever, 85 the rear end of the pawl being arranged to be engaged by the said extension, whereby the lever is adapted to lift the pawl out of engagement, and a check-pawl, substantially as described.

In testimony that I claim the foregoing as my own I have hereto affixed my signature in the presence of two witnesses.

CHAS. J. WAGNER.
